UNITED STATES PATENT OFFICE.

HARVEY F. CRAWFORD, OF BROCKTON, MASSACHUSETTS, ASSIGNEE OF ONE-HALF TO
GEORGE H. SNOW, OF BROCKTON, MASSACHUSETTS.

INNERSOLE FOR WELTED SHOES.

1,029,278.

Specification of Letters Patent. Patented June 11, 1912.

Application filed December 13, 1911. Serial No. 665,543.

To all whom it may concern:

Be it known that I, HARVEY F. CRAWFORD, a citizen of the United States, and a resident of Brockton, in the county of Plymouth and State of Massachusetts, have invented certain new and useful Improvements in Innersoles for Welted Shoes, of which the following is a specification.

This invention relates to a welted shoe, the inner sole of which is stiffened at its shank portion by the application to its under side of a metallic stiffener, usually composed of a strip or strips of sheet steel, the stiffener being interposed between the under surface of the inner sole and the upper surface of the outer sole.

It is the usual practice to place the stiffener upon the under surface of the inner sole after the upper and welt have been secured by the inseam stitches to the lip of the inner sole, the said parts being at this time on the last and the stiffener being secured in place by tacks or small nails driven into the inner sole. The outer sole is then applied and secured as usual. Much difficulty has been experienced owing to the tendency of the forward end of the shank stiffener to work downwardly and cut into the portion of the outer sole beneath it, the stiffener in many cases cutting entirely through the outer sole and practically spoiling the shoe. It is practically impossible to positively secure the stiffener to the inner sole after the lasting and inseam stitching operations by an adequate fastening device seated on the upper surface of the inner sole so that it cannot be pulled through the latter toward its under surface, and before the application of the outer sole, because the inner sole is then on the ordinary wooden last so that the upper surface of the inner sole is not accessible to enable an adequate fastening device to be seated on its upper surface. Any fastening device driven through the shank stiffener from the under surface of the inner sole and clenched upon the upper surface of the inner sole during the act of driving, would necessarily leave a rough and irregular portion of the device on the exposed upper surface on the inner sole which would be objectionable in appearance and liable to injure the stocking or the foot. Moreover, it is practically impossible to clamp a fastening device on the upper surface of an inner sole while the

ordinary wooden last is in the shoe, a condition that must prevail at the time when the stiffener is applied and secured.

The shank stiffener can not be secured to the inner sole before the inner seam is formed because it would be in the way of the needle of the sewing-machine which forms such seam. Heretofore, the only fastening that has been provided for the forward end of the shank stiffener has been afforded by a tack or nail driven through the stiffener into the under surface of the inner sole and having no positive engagement with the latter, so that the fastener becomes loosened when the shoe is in use and permits the forward end of the stiffener to cut through and into the outer sole.

My invention consists in an inner sole for a welted shoe provided at the forward portion of its shank part with a stiffener-securing member having a head portion seated on the upper surface of the inner sole so that it cannot be pulled through the sole toward its under side, and a body portion extending through the sole and projecting from its under surface between the side portions of the usual lip which receives the inseam stitches, the projecting portion of said member having means for engaging the forward end portion of a shank stiffener and positively securing it to the inner sole without affecting the flexibility of the sole, the said stiffener-securing member being applied to the inner sole before the lasting and inseam forming operations and engaged with the stiffener after said operations.

Of the accompanying drawings which form a part of this specification,—Figure 1 represents a bottom plan view of a portion of an inner sole provided with a stiffener-securing member in accordance with my invention, the sole being ready for lasting; Fig. 2 represents a section on line 2—2 of Fig. 1; Figs. 3 and 4 represent views similar to Fig. 2 showing modifications; Fig. 5 represents a bottom view of a partially completed lasted shoe, the inner sole of which is provided with a stiffener-securing member, as shown by Figs. 1 and 2; Fig. 6 represents a section on line 6—6 of Fig. 5; Fig. 7 represents a section on line 7—7 of Fig. 5; Fig. 8 represents a perspective view showing another modified form of the stiffener-securing member; Fig. 9 represents a sectional view showing the member shown by Fig. 8 at

tached to the inner sole; Figs. 10 and 11 represent perspective views of another modified form of stiffener-securing member, the same being made in two parts. Fig. 12 represents a sectional view of a portion of an inner sole provided with the stiffener-securing member shown by Figs. 10 and 11.

Similar reference characters indicate the same parts in all the figures.

10 In the drawings, 12 represents an inner sole for a lasted shoe, having the usual lip 13 which receives the inseam stitches 14 (Fig. 7) connecting the upper 15 and welt 16 with the inner sole.

15 In Figs. 1, 2, 3, 5, 6 and 7, 17 represents a stiffener-securing member which is secured to the forward part of the shank portion of the inner sole before the latter is applied to the last 18. Said fastening member 20 has a head which is seated upon the upper surface of the inner sole and resists movement of the securing member downwardly or toward the under surface of the inner sole. The body portion of the securing member extends through the inner sole and projects from the under surface thereof, its projecting portion being adapted to engage the forward end portion of a shank stiffener 19 and hold the same positively against the under surface of the inner sole.

In the embodiment of my invention shown by Figs. 1, 2, 5, 6, and 7, the securing member 17 is an ordinary bifurcated rivet, the head portion of which bears on the upper surface of the inner sole, while the bifurcated shank portion passes through the inner sole and projects from the under surface thereof, the parts or bifurcations of 40 the shank or body portion being bent outwardly in opposite directions to form ears 17^a which are spaced from the under surface of the inner sole sufficiently to receive, between their upper sides and the said under surface, the arms or divisions 19^a formed on the forward end portion of the stiffener 19 by a slot in said end portion, as shown by Fig. 5, said slot being open at the forward end of the stiffener and having a 50 closed inner end. The open end of the slot receives the shank portion of the securing member when the stiffener is moved endwise to its final position, and the closed end of the slot abuts against said shank portion and limits the said endwise movement. The ears 17^a, which are hereafter referred to as the inner head, are preferably bent to form said head before the lasting and inseam stitch-forming operation, said 55 ears being thus disposed so that they do not interfere with the curved needle of the sewing-machine which forms the inseam stitches. The sole provided with the securing member 17 is lasted with the upper and welt as usual, the upper and welt being

secured to the lip 13 before the stiffener 19 is applied. After the inseam has been formed and trimmed, the stiffener 19 may be applied by sliding its arms 19^a under the ears 17^a, as indicated by Figs. 5, 6, and 7. The rear end portion of the stiffener may be secured in the usual way by one or more small tacks or nails 20 driven from the under side of the stiffener into the inner sole. The rear end of the stiffener requires no positive fastening, the fastening 20 being employed simply to hold the rear portion of the stiffener in place while the outer sole is being applied and secured. The forward end of the stiffener, positively secured, as described, to the inner sole, cannot work loose or move endwise independently and cut into the outer sole, independent endwise movement of the said end being prevented by the bearing of the closed end of the slot on the shank portion of the securing member, while sidewise movement of the stiffener outwardly from the inner sole is prevented by the bearing of the arms of the stiffener on the ears 17^a.

In Fig. 3 I show the securing member inserted in the inner sole without having its divisions bent outwardly to form the ears 17^a, this bending being accomplished after the application of the stiffener to the inner sole. In other words, the ears 17^a may be bent or clenched over the under surface of the stiffener after the latter has been applied to the sole, instead of being bent to form the ears or inner-head 17^a before the application of the stiffener.

In Fig. 4 I show a fastening member composed of a staple 17^b, the neck of which constitutes a head seated on the upper surface of the inner sole, while the legs are driven through the sole and project from its under surface so that they may be bent into position to engage the stiffener either before or after the application of the stiffener to the inner sole. It will be seen that the portion of the fastening member which projects from and is immediately adjacent to the under surface of the inner sole constitutes a stop against which the inner end of the slot in the stiffener bears, said stop limiting the forward endwise movement of the stiffener, and that the inner head of the fastening member is spaced from the under surface of the inner sole by said stop and holds the inner end of the slot against the stop. The bearing of the outer head of the securing member on the upper surface of the inner sole holds the said member against pressure exerted by the stiffener on the inner head, so that no means are required at the under surface of the inner sole for holding the securing member in place. The projection of the inner head from the under surface of the inner sole is therefore reduced to the mini-

mum, so that said head does not form an objectionable protuberance liable to interfere with the outer sole.

The stiffener-securing member, above described, in each case has a two-part body portion, the inner head which engages the stiffener being composed of the outwardly bent extremities of the said parts. In Figs. 8 to 12, I show modifications accomplishing the same result without employing a stiffener-securing member, the body portion of which is bifurcated.

Figs. 8 and 9 show a stiffener-securing member which is a rivet having a tubular shank or body portion 17^a, the outer end of which is adapted to be upset or spread to form a practically continuous or annular head 17^e adapted to engage the shank stiffener.

In Figs. 10, 11 and 12, I show a stiffener-securing member composed of a rivet having a slotted shank or body portion 17^f provided with a reduced end 17^g, and a shoulder 17^h. A washer 17ⁱ is placed on the reduced portion 17^g against the shoulder 17^h and secured by upsetting the said reduced portion, said washer forming the inner head.

In each of the above-described embodiments of my invention, the stiffener-engaging member has a finished outer head which is embodied in and is substantially flush with the upper surface of the sole, and a body portion extending through the sole and projecting from the under surface thereof, said body portion being provided at its inner end with an inner head slightly spaced from the under surface of the sole and adapted to confine a slotted shank stiffener against the under side of the sole without affecting the flexibility of the part of the sole to which it is attached.

I am aware of the Murray Patent, Number 92,634, showing a plate attached to the under surface of an inner sole, said plate having a downwardly projecting pin adapted to engage one end portion of a shank stiffener. The plate is of considerably greater area than the pin and is attached at a plurality of points to the sole so that it materially stiffens and detracts from the

flexibility of the shank portion of the sole. My improved stiffener-supporting member, composed of a finished head seated on the upper surface of the inner sole, and a body portion extending through the sole and provided with an inner head, is adapted to secure a shank stiffener against the under surface of the sole without affecting the flexibility of the sole, and without forming an objectionable protuberance on the under surface thereof.

I claim:

1. An inner sole for a welted shoe provided at the forward portion of the shank part with a stiffener-engaging member composed of a finished outer head embedded in and substantially flush with the upper surface of the sole, and a body portion extending through the sole and projecting from the under surface thereof, said body portion being provided at its inner end with an inner head slightly spaced from the under surface of the sole and adapted to bear on the under side of a slotted shank stiffener and confine said stiffener against the under side of the sole without affecting the flexibility of the sole.

2. An inner sole for a welted shoe provided at the forward portion of its shank part with a stiffener-engaging member composed of a finished outer head embedded in and flush with the upper surface of the sole, and two prongs integral with said head and extending through the sole and projecting from the under surface thereof, the outer ends of said prongs being bent outwardly in opposite directions toward the edges of the sole to form ears slightly spaced from the under surface of the sole and adapted to bear on the under side of a shank stiffener, the said member being adapted to confine a slotted stiffener against the under side of the sole without affecting the flexibility of the sole.

In testimony whereof I have affixed my signature, in presence of two witnesses.

HARVEY F. CRAWFORD.
